JERSEY.

MACHINE FOR USE IN THE MANUFACTURE OF BOOTS AND SHOES.

1,163,599.

Specification of Letters Patent.

Patented Dec. 7, 1915.

Application filed November 22, 1912. Serial No. 732,971.

To all whom it may concern:

Be it known that I, JAMES CAVANAGH, a citizen of the United States, residing at Boston, in the county of Suffolk and State 5 of Massachusetts, have invented certain Improvements in Machines for Use in the Manufacture of Boots and Shoes, of which the following description, in connection with the accompanying drawings, is a specification, like reference characters on the drawings indicating like parts in the several figures.

This invention relates to machines for lasting shoes and is herein shown as embodied in a machine adapted to be operated 15 in part by hand and to be carried about the periphery of the shoe during the lasting operation.

It has been customary, in the operation of 20 lasting shoes, to employ hand pincers by which the upper is tensioned about the last and brought into position over the last to be secured by driving tacks through the upper and insole into the last, the tacks being left 25 upstanding, in lasting welt shoes, so that they may be removed prior to the inseaming or welting operation. Attempt has also been made to provide hand pincers of the kind referred to with tacking mechanism more or 30 less automatic in operation by which the lasting tacks were to be fed and driven after the upper had been properly tensioned by the pincers.

The use of lasting tacks is, of course, in 35 itself objectionable in the foreparts of welt shoes as the tacks constitute only temporary fastenings for holding the upper to the last while it is in temper and causing it to conform to the last so that when it dries out 40 the tacks may be partly removed without the upper drawing away from the last to a great extent. The repeated driving of the lasting tacks into the last soon destroys the holding power of the wood and renders the 45 last useless, necessitating the replacement of the lasts at great expense. As a usual practice the heavy lasting tacks also are removed and replaced by a smaller number of slender stay tacks before the operation of sewing on the welt is performed, as the heavy lasting tacks get in the way of the needle of the welt and cause frequent breakage.

A general object of this invention is to improve lasting apparatus, and more par-

ticular objects are to improve apparatus by 55 which an upper can be lasted and fastened without the use of the above-mentioned lasting tacks and to combine manually controlled upper tensioning means with power driven upper fastening means. 60

One important feature of this invention consists in the combination with pincers for pulling an upper over a last and means for inserting fastenings in a plane substantially 65 parallel to the last bottom in position to connect the upper to the lip of an insole of power operated mechanism constructed and arranged to insert a fastening and then come automatically to rest.

A further feature of the invention 70 consists in manually operated means for seizing and tensioning a portion of an upper about a last combined with mechanism operatively connected with said means for inserting a staple horizontally through the upper and 75 the channel lip of an insole. In the illustrated embodiment of the invention the staple inserting means is power operated; also the upper tensioning means comprises hand pincers, and a controller for the power 80 operated stapling mechanism is arranged to be manipulated by the hand of the operator which manipulates the pincers.

Another feature of the invention 85 comprises an anvil which co-operates with fastening inserting means to clamp a fastening and which is moved toward the fastening inserting means to clamp the channel lip and the upper together during the fastening 90 inserting operation. As shown, the anvil is 95 mounted on a carrier which moves it against the channel lip on the inner side, and a resilient connection is provided between the anvil and its carrier so that at first the anvil exerts a yielding clamping pressure and subsequently, as the carrier continues its movement toward the channel lip, becomes unyielding to resist the action of the driver and co-operates therewith in clenching the fastening. 100

Another feature of the invention consists in the combination with means for inserting fastenings, and means for pulling an upper over a last, of means for pressing together the upper and the channel lip of an insole, 105 comprising means to enter the angle of union between the feather of the insole and the channel, and forcing the upper into the

angle in advance of the fastening inserting operation.

Other objects and features of the invention including certain details of construction and more important combinations of parts will be apparent from a consideration of the following description when read in connection with the accompanying drawings, and will be pointed out in the claims.

10 In the drawing Figure 1 is a side elevation of the machine partly in section; Fig. 2 is a perspective view, partly in section, of portions of the staple forming mechanism.

The cams from which the various mechanisms are operated are connected to a main driving shaft 2 mounted in bearings in the frame or head 4. Motion is communicated to the shaft 2 from a bevel gear 6 having a shaft 8 which may be connected to any convenient source of power, for example, by a flexible shaft. Preferably the machine will be suspended from a loop 10 upheld by means of a spring or counterweight to relieve the operator of a portion or all of the weight 25 of the fastener forming and inserting mechanism. The bevel gear 6 meshes with a bevel gear 12 which is loose on the shaft 2.

A sleeve 14 is splined upon the shaft 2 and carries pins 16 adapted to engage recesses in the gear 12 whereby motion is communicated from the gear 12 to the shaft 2. The sleeve 14 is held in engagement with the gear 12 by a spring 18 and is withdrawn from engagement by a pin 20 acting in a groove 22 formed in the sleeve. A trigger lever 24 carries a spring-held plunger 26 which engages a groove in the pin 20 which is normally upheld by a spring 28. It will be seen that movement of the lever 24 will draw down the pin 20, thereby releasing the sleeve 14 which, in response to the pressure of the spring 18, slides into engagement with the gear 12, movement of which is then communicated to the shaft 2 by the sleeve 14, to operate the fastener inserting mechanism. As the lever 24 is moved farther, however, the plunger 26 becomes disengaged from the groove in the pin 20, allowing it to snap back into the groove of the collar 14, the shape of which is such that the collar 14 is moved to the left, Fig. 1, as it rotates to cause disengagement of the pin 16 from the gear 12 and consequent stopping of the fastener inserting mechanism.

55 The frame 4 carries a foot 30, pivoted at 31 to the frame of the machine, which is adapted to rest upon the insole of a shoe and to form a fulcrum for the action of the pincers which are pivoted at 32 to the frame 60 4. The pincer jaws 34, 36 are pivoted to each other at 38 and are provided with handles 40, 42 (shown broken away in Fig. 1), by which they are operated. Movement of the pincers about the pivot 32 is restricted by a pin 44 on the machine frame which engages

a slot 46 formed in the pincers and curved about the pivot 32 as a center.

The fasteners driven by the fastener inserting mechanism are preferably in the form of staples and, for the purpose of exemplification, mechanism is herein shown for forming such staples automatically from a coil of wire. The mechanism shown is constructed and arranged to drive a staple through the upper while held in tensioned condition by the pincers and through the channel lip or the shoulder of the insole of the shoe and to clench the staple upon the inside of the channel lip or in the inside channel.

75 The staple forming mechanism herein shown comprises an outside former 54 arranged to slide in a guideway 56 in the head of the machine, this guideway being formed preferably in a plate 58 which is fastened to the under side of the machine head. The outside former 54 is constructed and arranged to embrace an inside former 66 as it moves forward, and to form around the inside former a length of wire which has 80 previously been fed into position to be acted upon by the said outside former.

85 The wire which is to form a staple is preferably severed in advance of the staple forming operation, and the illustrated means for severing the wire comprises a cutter 68 carried by the outside former, the said cutter co-operating with a wire guide 70. The outside former is moved into co-operative relation to the inside former to form a staple by means 90 operated from a cam groove 74 in a cam block 76 on the shaft 2, said means comprising a lever 78 pivoted between its ends at 95 80 to the machine frame and connected by a link 82 to the outside former 54. The groove 84 in the outside former which receives the inside former 66 is enlarged at its lower side so that it forms a guiding groove for the staple when it is being driven and also a guiding groove for the staple driver 100. Below the enlarged lower portion of the groove in the outside former there is a solid portion 86 of the outside former which closes the groove and forms a support for the staple driver 100, this portion being extended 105 at the front of the outside former to form a tongue 110 having a function hereinafter to be referred to.

110 The staple driver 100 is operated from a cam groove 102 in a cam block 104 through a lever 106 pivoted between its ends at 108 to the machine frame and connected to the driver by a link 112, as clearly shown in Fig. 1. A stiffening rib 114 upon the driver 100 is received by the groove 84 in the outside former. As the staple driver 100 is moved forward by the connections just described to drive the staple, the inside former 66 is moved up out of the way of the driver, said inside former being carried by a bolt 115 120 125 130

92 arranged to slide vertically in a guideway 94 in the machine head, the said bolt having a reduced portion at its upper end which is inclosed by a sleeve 96 and carries 5 a pin 97 which engages slots in the sleeve 96, the pin being held normally at the bottom of the slots by a spring within the sleeve, as shown in Fig. 1. The upper end of the sleeve 96 carries a cam-roll which engages a 10 suitably formed cam path in the rear end of the cam block 76. This cam path is shaped to raise and lower the inside former in proper time relation with the reciprocation of the outside former.

15 The forward end of the guideway for the outside former and for the staple driver is formed as a nose 120 which is so shaped that it will crowd the upper into the angle between the rib of the insole and the projecting feather, without interfering with the 20 operation of the lasting pincers, and will guide the staple in a substantially horizontal direction through the upper and channel lip of the insole of the shoe, the guideway in said nose being in line with the 25 clenching end of the staple clencher 126 which is pivoted at 128 to the lower end of a lever or carrier 130 which is pivoted between its ends at 122 to the machine frame 30 and at its upper end carries a roll which operates with a face cam 133 formed on the front end of the cam block 76. The staple clencher 126 carries a rearward extension 136 which is held against a stop 138 formed 35 on the lever 130 by a spring 140. This construction affords a yielding pressure of the staple clencher 126 against the lever 130 to provide for variations in the thickness of the material between the nose of the staple 40 forming mechanism and the channel engaging end of the clenching member. The clenching member is normally held away from the rib of the insole by a spring 142 and is moved toward the nose of the staple 45 forming mechanism at the time the staple is driven by the action of the face cam 133 on the upper end of the lever 130. The clenching member or anvil acts to press the upper and the channel lip together before 50 and during the operation of inserting the fastening, and, after the lever or carrier 130 has moved far enough to take up the yield of the spring 142, the anvil is held unyieldingly against the rear face of the channel 55 lip to coöperate with the driver in clenching the fastening.

The nose 120 of the staple former is preferably formed in two parts, a lower part which contains an extension of the guideway 60 56 for the outside former and an upper part which is formed with an extension of the T-shaped groove in the outside former for the accommodation of the driver, the said outside former being arranged to move into approximately abutting relation to the rear 65 end of the upper part of the nose during the staple forming operation. The forward end of the upper part of the nose 120 overhangs the lower part, and the tongue 110 upon the outside former is constructed and arranged to extend beyond the front end of the lower part of the nose when the outside former has completed its staple forming operation, and thus close the lower side 70 of the staple and driver guiding opening in 75 the nose at the same time that it engages the upper and tucks it into the angle of union between the channel lip and the feather of the insole. The tongue 110 is tapered on its under side so that it tends to ride up over 80 the edge of the insole as it presses the upper into position to receive the staple, this movement of the tongue serving also to move the shoe and last relatively to bring the parts into such position that the staple 85 is guided through the upper and channel lip in a line above the path of movement of the needle of the welter in the welt stitching operation. It will be noted also that the tongue 110 has a wiping as well as a pressing or tucking action as it comes forward, the upward taper at the forward end of the tongue serving also to prevent injury to the upper as it is wiped over the corner of the 90 last.

95 The wire 150 from which the staples are to be formed may be carried by a reel 152 mounted on a suitable bracket extending from the frame 4 of the machine. The wire is fed to the staple forming mechanism by 100 a gripping mechanism comprising a slide 154 and a coöperating link 156, mounted in ears on the slide 154 and having its upper end pivoted at 158 to the lower end of a lever 160 which is pivoted to the machine 105 frame between its ends at 162 and at its upper end is connected by a curved slot and pin connection, as shown in Fig. 2, with a connecting rod 164 having a slot which embraces the cam shaft 2 and a pin 166 which 110 coöperates with a cam path formed in one face of the cam block 104. Movement is thereby communicated to the lower end of the lever 160 which operates, when moving to the left, Fig. 2, first to swing the link 156 which has a gripping edge 157 that coöperates with the upper face of the slide 154 to grip the wire. Further movement of the lever 160 carries the slide and wire forward and feeds the amount of wire required to 115 120 form a staple to the staple forming mechanism. Retraction of the wire fed is prevented by a one-way clutch comprising the member 170 mounted in an inclined groove 172 and held in engagement with the wire 125 by a suitable spring. It will be obvious that this device permits the feeding of the wire toward the staple forming mechanism, but prevents movement of the wire in the opposite direction. The amount of wire 130

fed to the staple forming mechanism, and hence the length of the staple, may be adjusted by changing the position of the end of the connecting rod 164 in the slot 161 in the upper end of the lever 160.

5 The machine is particularly adapted for lasting the sides of welt shoes but also may be used for lasting turn shoes. In the use 10 of the machine the shoe is supported by a suitable jack, and the foot 30 is rested upon the insole of the shoe, and the pincers are moved above the pivots 31, 32 to seize and tension upwardly a portion of the shoe upper. The mechanism for inserting fastenings 15 is positioned vertically and horizontally relatively to the shoe insole by the anvil 126 and the nozzle 120, and when the upper is properly tensioned a trip 24 is operated to set the clutch, whereupon the 20 mechanism operates to press the upper and channel lip together and to form and insert a staple through the upper and channel lip and to clinch the staple against the anvil 126. The mechanism then comes to rest, 25 and the pincers may be released and the machine moved into position to enable another portion of the upper to be similarly tensioned and fastened.

30 The improvements in methods of making shoes disclosed in this application are not claimed herein but constitute the subject matter of applicant's copending application Serial No. 862,211, filed September 17, 1914.

35 Having described my invention, what I claim as new and desire to secure by Letters Patent of the United States is:—

1. In a machine of the class described, 40 pincers for seizing an upper and tensioning it over a last, means for pressing together the upper and the channel lip of a welt shoe insole, and means for inserting a fastening through the lip and upper in a direction substantially parallel to the bottom of the 45 insole while they are pressed together and through the portion of the upper to which tension is being applied.

2. A machine of the class described, 50 having in combination, means for inserting fastenings comprising a nose arranged to engage against the upper of a shoe and press it against the shoulder of the insole, an anvil opposite said nose and adapted to engage in the inside channel of the insole and against the lip, means for moving the anvil to press the lip against the nose, pincers arranged to tension the portion of the upper which extends between the nose and the anvil, and means to drive a fastening.

60 3. A machine of the class described, 55 having in combination, a fastening guiding nose, a clinching tool movable toward and from said nose, means for tensioning the upper between the nose and the clinching tool, 65 a tucking wiper movable toward and away

from the clinching tool, means for effecting relative work clamping movement of said nose and said clinching tool before the fastening is inserted, and means for operating the parts to insert and clinch a fastening.

4. A machine of the class described having, in combination, pincers constructed and arranged to work an upper over a last having a welt shoe insole on the last bottom, mechanism arranged relatively to said pincers to press together the upper and the lip of the insole and to drive a staple substantially parallel with the last bottom through the upper and the lip and clinch the staple at the inner side of the lip, and power 80 driven mechanism arranged to operate said stapling mechanism to insert one staple and then come automatically to rest.

5. In a machine of the class described, a fastening guiding nose, a clinching tool 85 movable automatically toward and away from said nose, a tucking tongue movable toward and away from the clinching tool, and pincers arranged to tension the upper about the last in a plane lying between the 90 nose and the clinching tool.

6. A machine of the class described, having in combination, pincers adapted to tension an upper into position to be secured, fastening inserting means constructed and arranged to drive a fastening through the upper and the channel lip of the insole of a shoe, means for clinching the fastening upon the inside of the lip, and means for automatically operating the clinching tool 100 toward and away from the fastening inserting means in time relation to the operation of the inserting means.

7. A machine of the class described, having in combination, means for seizing and 105 tensioning about a last a portion of the upper of a shoe, fastening inserting means operatively connected with said seizing and tensioning means and arranged to drive a fastening in a horizontal line through the upper and insole channel lip, resiliently mounted means for clinching the fastening 110 upon the inside of the lip, and means for moving the clinching means toward and from the lip.

8. A machine of the class described, having in combination, staple forming and inserting means arranged to insert a staple through the upper and insole channel lip of 120 a shoe, means movable into and out of position to clinch the staple, means for tensioning the portion of upper through which the staple is to be driven, and means constructed and arranged to enter the angle of union 125 between the feather of the insole and the channel lip for forcing the upper into the angle in advance of the staple inserting operation.

9. A hand lasting machine, having in 130 combination, hand lasting pincers arranged

for seizing a portion of upper and tensioning it about a last, means combined with the pincers for forming a staple, means for inserting the staple through the tensioned upper and the channel lip of the insole, said means comprising a nose for guiding the staple and means for clutching the staple upon the inside of the channel lip, and means for wiping the upper over the edge of the last and tucking it into the angle of union between the channel lip and the feather of the insole constructed to position the staple above the path of movement of the needle of the welt.

15. 10. A lasting machine, having in combination, means for tensioning an upper, means for pressing an upper into the angle between the channel lip and the feather of the insole, means operated automatically for pressing the lip locally toward the tensioned upper, and means for inserting the fastening through the portion so pressed.

11. A lasting machine, having in combination, upper tensioning means, means for inserting a fastening through the tensioned upper and the channel lip of an insole, and means for automatically applying a resilient pressure to the tensioned upper and the channel lip in advance of the fastening inserting operation and at the point of which the fastening is inserted.

12. A lasting machine, having in combination, means for tensioning an upper into lasted relation to the channel lip of an insole, and fastening inserting mechanism comprising a nose or throat, a clutching tool constructed to enter behind the channel lip or in an insole channel and normally separated from said nose or throat, means for moving the clutching tool automatically into work clamping relation to the nose or throat, a driver operated through said nose or throat, and means whereby the said parts may be freely adjusted to bring them into proper relation to the shoe which is being operated upon.

13. The combination with hand pincers to be operated and guided by hand, of fastening forming and inserting mechanism operatively combined with the pincers arranged to insert fastenings transversely of the channel lip and adapted to be connected with a source of power, and a trip on the pincers for controlling the operations of the fastening inserting mechanism.

14. A device for hand lasting, comprising in combination, pincers having operating handles and curved jaws for working an upper over a last having thereon a lipped insole, fastening forming and inserting mechanism arranged to insert separate fastenings transversely of the lip, operating means for said mechanism, and means located adjacent to said handles for controlling the operating means.

15. A hand lasting device, having in combination, pincers to be operated by hand to tension the upper locally at successive points over a last having thereon a lipped insole, means for automatically forming and inserting successively separate fastenings, and means arranged to be operated by the hand of the workman which operates the pincers for controlling the fastening inserting mechanism.

16. A device of the class described, having in combination, pincers for seizing and tensioning an upper, a shaft, cams on the shaft, staple forming mechanism operated from said cams, an anvil against which the staples are clenched, and a cam on the shaft for moving the anvil toward the staple forming mechanism at the time when the staple is being driven.

17. A device of the class described, having in combination, pincers for seizing and tensioning an upper, a shaft, a cam on the shaft, a lever operated by the cam and carrying an anvil, a resilient connection between the lever and the anvil, and fastening inserting mechanism for forming and inserting fastenings and clutching them against the anvil.

18. A lasting machine, having in combination, a frame, an abutment on the frame adapted to rest on the insole of the shoe, pincers pivoted to the frame at a point below the pivot of the pincer jaws, and fastening inserting mechanism mounted on the frame and disposed adjacent to the jaws of the pincers.

19. A device of the class described, having in combination, pincers, staple forming and driving mechanism comprising a cam shaft, a lever 160 operated from the cam shaft, a link 156 pivoted to the lever, a slide 154 pivoted to the link 156, and a wire passage between the link and the slide, the wire being gripped between the slide and the link and fed by movement of the lever.

20. In a lasting machine, the combination with hand manipulated pincers supported in the machine, of fastening inserting mechanism arranged relatively to the pincers to fasten the upper held by the pincers, means to relatively position the machine and shoe both horizontally and vertically, and power means to operate the fastening inserting mechanism.

21. In a lasting machine, the combination with hand manipulated pincers supported in the machine, of fastening inserting mechanism arranged relatively to the pincers to insert upper fastenings transversely of the insole channel lip, and means arranged to be controlled by the hand using the pincers to cause said mechanism to insert a fastening as described.

22. A machine of the class described, having, in combination, hand manipulated

- pinchers supported in the machine for movement by the operator to tension an upper at successive points over a last, means for inserting successively separate fastenings, and 5 means arranged to be operated by the workman for causing the fastening inserting mechanism to drive one fastening transversely through the lip and clench it and then come automatically to rest.
- 10 23. A device of the class described, having, in combination, pincers for seizing and tensioning an upper, a shaft, a cam on the shaft, a lever operated by the cam and carrying an anvil, a resilient connection between 15 the lever and the anvil, and mechanism for inserting fastenings and clenching them against the anvil.
24. A machine of the class described having, in combination, hand operated means 20 for seizing and tensioning about a last a portion of the upper of a shoe, means operatively connected with said seizing and tensioning means to insert a staple horizontally through the upper and channel lip of an 25 insole, and means for clenching the staple.
25. In a lasting machine, the combination with pincers for tensioning an upper into lasted relation to the channel lip of an insole, of fastening inserting mechanism comprising 30 a nose or throat, a clenching tool constructed to enter behind the channel lip or in an inside channel and normally separated from said nose or throat, means for moving the clenching tool automatically into 35 work clamping relation to the nose or throat, and a driver operating through said nose or throat.
26. A machine of the class described having, in combination, means for working an upper into position to be fastened to the channel lip of the insole, means for driving a fastening through the lip in a plane substantially parallel with the face of the insole, and clenching means comprising a carrier, an anvil member yieldingly mounted on the carrier, and means for moving the carrier to press the anvil against the inner side of the lip.
27. A machine of the class described having, in combination, means for working an upper into position to be fastened to the channel lip of an insole, means for driving a fastening through the lip in a plane substantially parallel to the face of the insole, and clenching means comprising a carrier, an anvil member mounted on the carrier, a spring permitting the anvil to effect an initial yielding clamping of the lip to the upper, and means adapted to render the final 60 clamping pressure unyielding.
28. A machine of the class described having, in combination, pincers constructed and arranged for hand manipulation to pull an upper over a last, means constructed and arranged to insert staples substantially parallel to the plane of the last bottom to fasten the upper to the channel lip of an insole, and an anvil arranged to clench the staples at the inner side of the channel lip. 65
29. A machine of the class described having, in combination, pincers constructed and arranged for manipulation to pull an upper over a last, means constructed and arranged to insert staples substantially parallel to the plane of the last bottom to fasten the upper to the lip of an insole, and an anvil arranged to clench the staples at the inner side of the channel lip, said pincers, anvil and stapling means being constructed and arranged relatively for the pincers to hold the upper while the stapling means inserts the staples and the anvil means clenches the staples. 70
30. A machine of the class described having, in combination, pincers for pulling an upper over a last, means for inserting separate disconnected fastenings in a plane substantially parallel to the last bottom in position to connect the pulled upper to the lip of an insole, and power operated mechanism constructed and arranged to drive and clenched one fastening and then come automatically to rest. 80
31. A machine of the class described having, in combination, pincers for pulling an upper over a last, means for inserting fastenings in a plane substantially parallel to the last bottom in position to connect the pulled upper to the lip of an insole, and power operated mechanism constructed and arranged to insert one fastening and then come automatically to rest. 90
32. A machine of the class described having, in combination, a frame, fastening inserting mechanism on the frame, an abutment on the frame adapted to rest on the insole, hand pincers mounted on the frame for limited movement about a horizontal axis located adjacent to and above the plane of the insole, and a pivotal connection between the frame and the abutment permitting swinging movement of the frame and pincers about a substantially vertical axis. 105
